DESIGN FOR A COMBINED PERFUME BOTTLE AND COVER

Janina Silston, New York, N. Y.

Application April 18, 1945, Serial No. 119,075

Term of patent 7 years

(Cl. D58—6)

To all whom it may concern:

Be it known that I, Janina Silston, a citizen of Poland, residing at New York, in the county of New York and State of New York, have invented a new, original, and ornamental Design for a Combined Perfume Bottle and Cover, of which the following is a specification, reference being had to the accompanying drawing, forming part thereof.

In the drawing:

Fig. 1 is a front elevational view of a combined perfume bottle and cover showing my new design;

Fig. 2 is a side or edge elevational view thereof; and

Fig. 3 is a top plan view thereof.

I claim:

The ornamental design for a combined perfume bottle and cover, as shown.

JANINA SILSTON.
